LAMINATED LIGHTING STANDARD

Edmund J. Schrang, 5454 N. Fort Washington Road,
Milwaukee, Wis.

Filed Apr. 12, 1965, Ser. No. 84,725

Term of patent 14 years

(Cl. D48—31)

The figure is a perspective view of a laminated lighting standard showing my new design as seen from the front and side.

The rear of the article is identical in appearance to the front, and the side not shown is identical in appearance to the side shown in the drawing. The broken line showing a luminaire and support arm is for illustrative purposes only.

This application is a continuation-in-part of design application Serial No. D. 77,125, filed October 23, 1963 and now abandoned.

I claim:

The ornamental design for a laminated lighting standard, as shown and described.
